US00D560203S

(12) United States Design Patent (10) Patent No.: US D560,203 S
Williamson et al. (45) Date of Patent: * Jan. 22, 2008

(54) COMBINED MEDIA PLAYER AND COMPUTER CONTROLLER

(75) Inventors: Paul Williamson, Providence, RI (US); James Corbin, Providence, RI (US); Gregor Mittersinker, Warwick, RI (US); Christopher Roman, Wrentham, MA (US); Michael Leighton, Sun Prairie, WI (US)

(73) Assignee: Numark Industries, LLC, Cumberland, RI (US)

() Term: 14 Years

(21) Appl. No.: 29/282,859

(22) Filed: Jul. 31, 2007

Related U.S. Application Data

(62) Division of application No. 29/246,271, filed on Mar. 28, 2006, now Pat. No. Des. 553,118.

(51) LOC (8) Cl. 14-01

(52) U.S. Cl. D14/168; D14/203; D14/217

(58) Field of Classification Search D14/135-136, D14/156, 162, 167-168, 199-203, 217, 261; 312/8.4, 322, 325; 84/645; 360/99.02, 99.07; 369/75.11, 75.21, 77.21, 77.11

See application file for complete search history.

(57) CLAIM

The ornamental design for a combined media player and computer controller, as shown.

DESCRIPTION

FIG. 1 is a perspective view of a combined media player and computer controller showing our new design;

FIG. 2 is a front elevational view thereof;

FIG. 3 is a rear elevational view thereof;

FIG. 4 is a top view thereof;

FIG. 5 is a bottom view thereof;

FIG. 6 is a left side elevational view thereof;

FIG. 7 is a right side elevational view thereof; and,

FIG. 8 is a rear perspective view thereof.
